UNITED STATES PATENT OFFICE.

GEORGE W. GETCHELL, OF BREWER, MAINE, ASSIGNOR OF ONE-HALF TO
MANLY HARDY, OF SAME PLACE.

BOILER FEED-REGULATOR.

SPECIFICATION forming part of Letters Patent No. 274,186, dated March 20, 1883.

Application filed September 12, 1882. (Model.)

To all whom it may concern:

Be it known that I, GEORGE W. GETCHELL, of Brewer, in the county of Penobscot and State of Maine, have invented certain new and useful Improvements in Boiler Feed-Regulators; and I do hereby declare that the following is a full, clear, and exact description of the invention, that will enable others skilled in the art to which it appertains to make and use the same, reference being had to the accompanying drawing, forming a part of this specification, in which is shown an elevation of my invention, partially in section.

My invention consists of an improvement on boiler feed-regulators, and will be readily understood by reference to the accompanying drawing, in which—

A shows a partial cross-section of a boiler with my improvement attached. At *b* is shown a pipe leading from the upper portion of the boiler above the normal water-line, and at *c* a corresponding pipe below the water-line, both connecting with a cylinder, *d*. A pipe, *e*, enters the upper end of this cylinder, connecting with and furnishing steam to operate the feed-pump. This pipe, at its end within the cylinder, is provided with a valve-seat, *f*, receiving a valve, *g*, working within said cylinder. At *h* is a short tube suspended on pivots *h'*, or otherwise balanced across said cylinder, so as to move freely upon said pivots, either end being capable of depression. Within this tube is a ball, *x*, capable of rolling from one end to the other as either is lowermost. At *i* is a float moving upon a rod, *j*, in the cylinder *d*, between collars *k k'*, fixed upon said rod, and having a connection, *p*, acting upon one end of the tube *h* in such a manner as to elevate it when the water in the boiler reaches the desired height. To this tube *h* is also attached a connection, *q*, acting against the valve *g*, so that when one end of the tube *h* is raised by the action of the float, and the ball *x* by its weight rolls to the opposite end, the valve *g* is raised and forced into its socket in the end of the pipe *e*, cutting off the supply of steam from the feed-pump, and consequently the supply of water to the boiler. When the water becomes low the float *i* drops, drawing down the tube and opening the valve *g*, working the

feed-pump, and supplying water to the boiler through the pipe *o*.

It will be observed that the operation of my invention does not depend altogether upon the buoyancy of the float. When the latter is sufficiently raised by the incoming water it inclines the tube through its connection *p*, the inclosed ball rolling to the free end thereof, and bringing to sufficient weight when there to overbalance the weight of the float, rod, and valve, forcing the latter instantaneously into its seat. As the float falls, however, when the water gets below a certain height, and ceases to sustain it, the weight of the float, rod, and valve inclines the tube in the opposite direction, returning the ball to its former position, permitting the valve to drop, and allowing the steam to enter. The connection or rod between the tube and valve need not be secured to the latter, but may be arranged to strike against and raise it as the tube is inclined, allowing it to fall of its own weight when the support is removed. This arrangement is ample when one, two, or more boilers are used, feeding equally. When, however, a gang of boilers are employed, some of which feed faster than others, it becomes necessary to cut off the water-supply from the boilers as they become full, lest the steam from the more slowly filling boilers should force an undue quantity of water into those filling more quickly. To do this I attach to the lower end of the cylinder *d* a valve-seat, *m*, into which, at *p*, I attach a pipe, connecting with and supplying the boiler with water from the feed-pump through a second pipe, *o*, leading to said pump. To the rod *j* in said cylinder I secure a valve, *l*, fitting into said valve-seat, and closing the pipe *p* when the float is raised by the inflow of water, said valve being operated in the same manner and at the same time that the valve *g* is operated. Proper guides may of course be employed to insure the vertical motion of the rod *j* and to retain it in a vertical position.

The rod *j* and attached valves may be supported at the proper elevation by any well-known mechanical means—such as by extending the lower end of the valve-stem to form a rest for it below the valve, by resting it, by means of a collar, upon one of the vertical guides, or by any other convenient device—

as, for instance, elongating the rod *j*, so that the lower valve, when the same is open, will rest on the bottom of the cylinder.

In cases where the steam produced by the boiler is not employed to operate the pump supplying water, but water is supplied by some other agency, it is evident that the upper valve, *g*, may be dispensed with, the lower valve controlling the water-supply, together with the float, and other mechanism remaining as shown and described.

Both valves are attached to the rod *j*, and supported by the tube, the ball being shifted to either end of said tube to hold the valves open or closed. When the upper valve is dispensed with, as stated, the tube may be connected directly with said rod *j*, operating through it upon the lower valve, as before set forth.

20. What I claim as my invention is—

1. In a feed-regulator for steam-boilers, the combination of the valve *g*, closing the pipe supplying steam to the feed-pump, with the float *i*, communicating at all times with both 25 the steam and water contained in the boiler, and supported by said water at or very nearly

at the level of the water-line of the boiler, balanced tube *h*, ball *x* therein, and connecting mechanism whereby said valve is operated by the combined action of said tube and float, 30 substantially as set forth.

2. In a feed-regulator for steam-boilers, the combination of the float *i*, tube *h*, and ball *x*, with the valves *g* and *l*, operating respectively to close the steam and water connections between the feed-pump and boiler, substantially 35 as set forth.

3. In a feed-water regulator for steam-boilers, the combination of the float *i*, rod *j*, tube *h*, and ball *x*, with the valve *l*, all operating as described, to check the flow of water to the boiler when the same has reached the desired height, and to admit it when the water becomes low, substantially as set forth and described. 40

In testimony that I claim the foregoing I have hereunto set my hand this 6th day of September, 1882.

GEORGE W. GETCHELL.
